UNITED STATES PATENT OFFICE.

WILLIAM BARDROFF, OF BALTIMORE, MARYLAND.

BLACKING-BRUSH.

No. 894,103.

Specification of Letters Patent. Patented July 21, 1908.

Application filed April 6, 1907. Serial No. 366,856.

To all whom it may concern:

Be it known that I, WILLIAM BARDROFF, a citizen of the United States, residing at Baltimore, in the county of Baltimore City and State of Maryland, have invented new and useful Improvements in Blacking-Brushes, of which the following is a specification.

This invention relates to brushes for applying liquid blacking to boots and shoes; and it has for its object to provide an improved device of this class comprising a receptacle or container, a brush for applying and distributing the liquid, a valve for controlling the flow of the liquid, and means for actuating the valve in a simple, convenient and efficient manner.

The invention consists in the improved construction and novel arrangement and combination of parts which will be herein-after fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a side view of a device embodying the invention, and showing the lid or cap partly raised. Fig. 2 is a vertical longitudinal sectional view. Fig. 3 is a transverse sectional view taken on the plane indicated by line 3-3 in Fig. 2. Fig. 4 is a transverse sectional view taken on the plane indicated by the line 4-4 in Fig. 2.

Corresponding parts in the several figures are denoted by like characters of reference.

The improved device includes a can or receptacle 1 made of light sheet metal and having a slightly convex resilient bottom 2 and a screw cap or cover 3. The latter is apertured for the passage of a stem 4 which extends axially through the can or receptacle and which carries at its inner end a disk or diaphragm 5 whereby it is guided within the can; said stem is also provided at its lower or inner extremity with an adjustable nut 6 adapted to bear against the inner surface of the resilient bottom 2 with which it is held in contact by the action of a spring 7 coiled upon the stem between the cap 3 and the disk 5. The cap 3 is provided with ports or apertures 8 adapted to be closed by a valve 9 mounted at the upper or outer extremity of the stem 4,

and held to its seat by the tension of the spring; said valve being provided with a packing disk 10 in order to effect a tight joint.

The cap 3 is provided with a tubular extension 11 in which the bristles 12 are held and is also provided with an axially disposed tubular member 13, flaring or funnel-shaped at its inner end as shown at 14, and through which liquid may flow from the ports 8 when the valve is unseated. The brush, when not in use, is protected by a lid or cap 15 exteriorly engaging the tubular member 11 and having a flaring or bell-shaped mouth 16 whereby it is adapted for ready engagement with the brush. A washer 17 is preferably interposed between the cap 3 and the upper edge of the can or container for the purpose of making a liquid tight joint.

In operation, the nut 6 is to be adjusted upon the stem 4 in such a manner that when the cap 3 is applied to the can the said nut will be disposed closely adjacent to, if not in actual contact with, the resilient bottom 2, but in such a manner that the valve 9 will be held upon its seat under the tension of the spring 7. The receptacle or container will thus be tightly closed by the cap 3 and the valve 9 jointly. To apply blacking, with which the container is supplied prior to the application of the cap, the receptacle or container is inverted after which the valve is unseated by exerting pressure exteriorly upon the resilient bottom, thus permitting liquid to flow through the ports 8 and the tubular passage 13-14 to the brush, which, when sufficiently saturated, is used for applying and spreading the blacking. When pressure upon the resilient bottom is relaxed, the valve will be reseated by the action of the spring 7.

It is preferred to provide the disk or diaphragm 5 with openings 18 in order that the flow of liquid may not be obstructed.

This improved device, as will be seen from the foregoing description, is very simple and convenient for use, and it affords a tight and convenient receptacle and applying device for liquid blacking and other liquids of a similar nature which it is desired to guard against evaporation, and which ordinarily cannot be readily applied without danger of soiling the fingers. By this device, the liquid may be neatly and efficiently applied; the contents is protected from evaporation; and the brush when not in use is protected from dust and injury.

Having thus fully described the invention, what I claim as new is:—

1. In a device of the class described, a container having a resilient bottom, a threaded cap or cover having ports, bristles connected with the cap and having a tubular passage communicating with the ports, a longitudinally movable valve carrying stem, a disk mounted upon the valve stem adjacent its lower or inner extremity and guided interiorly in the container, a spring coiled upon the stem between the cap and the disk, a nut adjustable upon the lower or inner extremity of the valve stem and contacting with the under surface of the disk and with the resilient bottom of the container.

2. A blacking brush comprising a container having a resilient bottom, a longitudinal movable spring actuated stem, a valve

carried by the stem, a guide member on the stem for engagement with the container, an adjustable device on the lower extremity of the stem, said device bearing against the under surface of the guide member, a threaded cap having ports, a tubular extension formed integral with the cap, a centrally disposed tubular member provided with a flaring portion and arranged to supply the blacking from the container to the bristles, said portion contacting with the inner surface of the tubular extension, whereby the opening movement of the valve is limited.

In testimony whereof, I affix my signature in presence of two witnesses.

WILLIAM BARDROFF.
